UNITED STATES PATENT OFFICE

2,103,963

MOTOR APPARATUS

Wade H. Wineman, Michigan City, Ind., assignor to Sullivan Machinery Company, a corporation of Massachusetts

Application July 21, 1933, Serial No. 681,543

14 Claims. (Cl. 121—47)

My invention relates to motor apparatus, and more particularly to automatic controlling means for such apparatus.

In certain oil fields there is a substantial quantity of oil available but the pressure of the oil is insufficient to raise the latter to the surface, and accordingly pumping devices must be used. A highly satisfactory system includes a plurality of pumping units all arranged within a reasonable area and all supplied with power operating medium from a central compressor having pipes leading out therefrom to the pumping units. In a preferred form of such apparatus, the unit at each well includes a pump head in the form of an expansible chamber motor connected with a piston type pump in the well. In the interest of economy, the air is customarily preheated at the well and is exhausted from the motor cylinders with considerable residual pressure and returned to the intake of the compressor for re-compression.

As it is not practicable to keep an operator at each well, it is important, not only that the pumping apparatus at each well be of a regular and positive type and not subject to derangement, but, moreover, to provide automatic devices which will govern the speed of the pump and will automatically shut down the pump in the event of breakage of the pump rod line or damage to the pump packings, or the like.

It is an object of my invention to provide an improved controlling mechanism for a pump unit of the character just mentioned, which shall operate automatically to interrupt the supply of motive fluid to the pump when necessary. It is another object of my invention to provide an improved controlling mechanism for a pumping unit of the type referred to which shall automatically preclude overspeeding of the pump unit.

It is a further object of the invention to provide an improved controlling apparatus for a pump unit of the character described which shall, having once interrupted operation of the pump as a result of a serious derangement of the latter, maintain the motive fluid supply to the pump interrupted until after repair of the pump and until deliberate re-starting of the pump is effected. Other objects and advantages of the present invention will subsequently appear.

In the accompanying drawings I have shown my broad invention embodied in two illustrative forms: one in which the sole function is the interruption of motive fluid supply to the pump and the keeping of such supply interrupted until

deliberately reinitiated, after derangement of the pump mechanism; in the other form, these functions have combined with them an automatic speed governing function.

In the drawings, in which these two illustrative embodiments are, as stated, illustrated—

Fig. 1 is a more or less diagrammatic view, with parts broken away, of a pumping system in which the first illustrative form of the invention is embodied.

Fig. 2 is a vertical central section through the automatic controlling valve which forms a part of this system.

Fig. 3 is a vertical section on the line 3—3 of Fig. 2.

Fig. 3a is a fragmentary sectional view through a portion of the upper end of the pump cylinder.

Fig. 4 is an elevational view, with parts broken away, of a system embodying the form of my invention in which not only automatic stopping, but also automatic speed governing, is effected.

Fig. 5 is a central vertical section through the automatic controlling valve which forms a part of this last system.

Referring to the drawings, and first to Figs. 1 to 3, inclusive, it will be noted that a pumping motor 11, which may advantageously be of the type disclosed in my copending application Serial No. 612,538, filed May 20, 1932, and which issued as Patent No. 2,004,146 on June 11, 1935, is supported in a suitable manner from a tower 12 of structural steel or the like. The motor 11 has an automatic inlet valve mechanism 13 and an automatic discharge valve mechanism 14. Motive fluid is supplied from a central compressor system or the like (not shown) through a pipe 15, passing through a preheater 16, past a stop valve 17, a vent valve mechanism 18, and an automatic controlling mechanism 19, hereinafter more fully described, and then through a pipe 20 to the inlet valve mechanism 13. The supply pressure may be advantageously of the order of 200 to 300 pounds per square inch. Exhaust from the pumping motor 11 passes, under the control of the exhaust valve 14, through a line 21 back to the intake of the pumping system (not shown). The back pressure in the exhaust line may be perhaps 80 pounds per square inch. The pumping motor 11 comprises a cylinder member 22 within

which a piston 23 is reciprocable under the control of the valve mechanisms 13, 14. The normal limit of upward travel of the piston 23 is indicated in Fig. 1, the piston usually stopping its upward travel in a position substantially below

a vent port 24. A pipe 25 leads from a point substantially above the vent port, to the automatic control apparatus 19.

The automatic control apparatus 19 comprises 5 a valve casing 27 whose opposite ends 27a and 27b are respectively connected, through suitable connections, with the preheater and with the pipe line 20. A septum 28 in the valve casing 27 provides a valve seat 29 upon which a valve member 30 is adapted to seat. The valve member 30 is supported upon the lower end of a valve stem 31 which passes through a gland 32 arranged in a cover member 33 for the casing 27. It will be observed that the flow through 10 the valve casing 27 is in such a direction as to hold the valve 30 seated when it has closed, but in view of the fact that the valve when open is well above its seat and there is a pressure of between 200 and 300 pounds, say, in the valve casing, acting upon an unbalanced area equivalent to the cross sectional area of the stem 31, the valve will remain open without difficulty. Above the casing 27 the cover member 33 supports a cylinder member 34 having a bore 35 open to the atmosphere at 15 its lower end and containing a piston 36 which is mounted upon the valve stem 31 and adapted, through engagement with a shoulder 37 upon this stem, to move the stem down and close the valve when the piston 36 is subjected to a sufficient 20 pressure upon its upper end. The area of the piston 36 is preferably made relatively large, so that a relatively small pressure acting downwardly upon the piston 36 will suffice to move the latter downwardly and close the valve 30. On 25 the other hand, the pressure built up above the piston 36 during normal upward movements of the latter is not high enough to overcome the pressure holding valve 30 open. The cylinder head 38 is provided with a passage 39 to which the pipe 25 leads, and is provided with a recess or counterbore 40, so arranged that nearly the 30 entire area of the upper side of the piston 36 may be subjected continuously to the pressure transmitted through the pipe 25.

40 A bypass 41 having a controlling valve 42 extends from the space below the valve seat 29 to the space above the valve seat, for purposes which will shortly be described. A handle or knob 43 is arranged on the upper end of the stem 31.

45 The mode of operation of the first species of the invention will now be apparent. It will be understood that the piston 23 is connected, through a piston rod 44 and suitable connections 45, with a sucker rod line 46 leading to a positive displacement type pump discharging on the up strokes (not shown). During the normal operation of the pumping system illustrated, pressure will pass from the pipe 15 through the preheater 16, through the normally open stop valve 17, through the vent device 18, whose vent valve is normally closed, into the casing 27, past the valve 30, which is held in raised position by the pressure within the casing, through the pipe 28 and, under the control of the admission valve mechanism 13, to the motor 11; and the motor will be operated, the piston 23 alternately rising to the position indicated in Fig. 1 and raising with it the pump plunger (not shown) to effect discharge of oil on the up stroke; and then, on 50 opening of the exhaust valve mechanism 14, descending, with its downward movement retarded suitably by the back pressure in the pressure discharge line 21. In the event that the pump rod line 46 should break, or in the event that the pump packings should suddenly begin to leak seriously, the piston 23 under the relatively great

5 pressure beneath the piston, no longer adequately offset by the load, would move upward very rapidly and create above the piston a substantial pressure, due to the movement of the piston so rapidly that the open vent means 24 could not discharge the air compressed without a substantial increase in pressure. Indeed, in case the piston passed the 10 vent port 24 a pressure of 15 pounds or more per square inch might result. During normal operation, as explained above, the vent means 24 was sufficient to prevent the building up of more than half a pound to a pound of pressure above atmospheric pressure above the piston 23. When the abnormal pressure is produced, however, as a result of the sudden releasing of the piston 15 from the major portion of its load, this pressure, transmitted through the pipe 28 to the top of the piston 36, will move the latter downwardly and effect closing of the valve 30. The valve 30, having been moved to its seat, will be held closed 20 by the pressure entering the casing, and accordingly there will be no tendency for this valve to be opened again except as it may be deliberately opened. When the pump rod line has been repaired or the pump cylinder removed and new 25 packings restored and the system again placed in working order, the operator will be able to open the valve 30, either by having the stop valve 17 closed and opening the vent 18, or by opening the bypass valve 42 and thereby equalizing the 30 pressure on opposite sides of the valve 30 so that the latter may be pulled up to open position by the stem handle 43.

35 It will be evident that the apparatus described will normally exert no effect on the operation of the pumping system, but will automatically shut down the pumping system, should the pump motor piston be relieved of its load, and will keep the pump motor shut down thereafter until an operator comes to discover and cure the difficulty 40 which resulted in the shutting down of the unit.

45 Now turning to the second species of the invention shown—that of Figs. 4 and 5—in which governing as well as automatic stopping is effected, it will be observed that the pumping apparatus in general is substantially the same as that shown in Fig. 1. In this case the automatic controlling valve mechanism is designated, generally, 50 and includes a valve casing 51 having an external wall 52 bounding a chamber 53 communicating with the line 20, and an internal wall 54 bounding a chamber 55 communicating with the preheater. The wall 54 has aligned bores 56 and 57 therein; and a valve 58 having portions 58 and 60, respectively adapted to close the openings 57 and 56, acts to control flow of fluid from chamber 55 to chamber 53. Suitable guide ribs 61 are formed on the valve to keep it centered. The valve has a stem 62 secured thereto which extends up through a gland 63 carried by the 60 lower end of a frame 64, which is held by screws 65 upon the top of the casing 51. Within the upper end of the frame member 64 is a cylinder 67, in which a piston 68 is reciprocable. The piston 68 is connected through a piston rod 69 with 65 the stem 62. The piston rod 69 is guided in a threaded follower or abutment member 70 which engages the lower end of a spring 71 which extends between the member 70 and the lower surface of the piston 68. The member 70 is threadedly secured in a transverse wall 72, which is of substantial thickness and provided with a series of recesses 73 in which relatively heavy springs 74 are seated. These springs extend upward a substantial distance into the lower end of the cylinder. 75

der chamber 67. An outer cover 18 is provided for the cylinder chamber 67 and has a lock-nut held threaded stop member 76 arranged therein and adapted to limit upward motion of the piston 68. A port 77 is connected by a line 78 with the space in the motor cylinder 11, substantially above the top point in the normal travel of the motor piston and preferably substantially above a vent 79, which is provided in the upper end of the cylinder 11. At the junction of the piston rod 69 and the valve stem 62 a washer or collar member 80 is provided, in a position to be engaged by a latch 81 pivotally connected at 82 to the bottom of the wall 12 and held by a spring 83 in position to move back into engagement with the upper part of the collar 80 as soon as the latter has passed below the lower end of the latch.

The mode of operation of this safety mechanism will be best understood by a description of the manner in which it is adjusted for operation. Suppose it is desired that the pump motor shall operate at the rate of 15 cycles per minute. Under these circumstances, the setscrew or stop member 76 will first be screwed down until the governor valve 58 is completely closed. The spring 71 is then adjusted to a high degree of compression by rotation of the follower 70. The motor throttle 17 is then opened wide and the stop member 76 is backed out until the governor valve is opened sufficiently by the spring 71 to permit 15 cycles of the pump per minute. Compression of the spring 71 is then slackened by screwing out the follower 70 until the vent pressure on top of the motor piston just tends to overcome the force exerted by the spring 71. This vent pressure is usually only from one half to perhaps one or two pounds per square inch; but the area of the piston 68 is substantial, and therefore the pressure exerted by the latter, in the event of even a relatively small rise in the pressure above the motor piston, will easily overcome the pressure of the spring 71 and the slight addition of unbalance due to the cross sectional area of the valve stem 62, and permit the throttle valve 58 to be closed. The parts are locked in the adjusted position just described.

Now if the pump begins to speed up on the up stroke, (this might occur if less oil were available, perhaps), the vent 79 will be inadequate to discharge the air from above the piston sufficiently rapidly to prevent some rise in the pressure above the piston 68. Accordingly, if the motor tends to speed up on its up stroke, as it would if it had a tendency to make more cycles per minute than desired, the pressure acting on the piston 68 will promptly partially close the governor valve 58 and thereby throttle the motive fluid supply and slow down the pump.

In the event that sucker rod breakage occurs, there will be a much higher upward speed of the motor piston and an almost instantaneous building up of a pressure above the motor piston sufficient to completely close the governor valve 58. In case the piston passes vent 79, a positive compression resulting in a pressure of perhaps 15 pounds per square inch will occur. This will operate to shut down the motor, and the motor will be held shut down because the latch 81 will engage the ring 80 and retain the governor valve in closed position. In the event that breakage of the sucker rod line occurs, downward motion of the piston 68 would be very sharp, and it is for this reason that the springs 74 are provided, for, though their length is such as to permit the necessary downward movement of the valve 68 to

effect closure of the valve 58, they will effectually cushion the downward movement of the piston 68, though they will yield sufficiently to permit the washer 80 to come below the latch 81. Ordinary pressure variation during normal slight speed changes in the operation of the pumping motor will not be sufficient to compress the springs 74 far enough to allow the washer 80 to pass below the point of the latch member 81.

In Figs. 1 and 4 the controlling mechanisms 19 and 50 have been shown at a point more remote from the inlet valve mechanism of the pump motor than would normally be used in practice, this being done to facilitate illustration.

From the foregoing description of the species of the invention shown in Figs. 4 and 5, it will be clear that I have provided a mechanism which is not only a safe automatic stop device and which is certain to shut down the motor in the event that breakage of parts causes complete closing of the governor valve, but which is also an effective governor, and which will limit the speed of the pumping motor satisfactorily and with reasonable closeness, without in any way lessening the capacity of the mechanism to serve as a stop device when that function becomes necessary.

While in this application I have specifically described two forms which my invention may assume in practice, it will be understood that these forms of the same are shown for illustrative purposes only, and that the invention may be modified and embodied in various other forms without departing from its spirit or the scope of the appended claims.

What I claim as new and desire to secure by Letters Patent is:—

1. In a pumping system, in combination, a single acting pumping motor having a load, fluid connections leading to said motor, controlling means for said connections normally yieldingly maintained in flow-permitting position but having associated releasable latch means by which it is held in closed position, when moved thereto, and means controlled by pressure built up in the non-working end of said pumping motor upon loss of pumping load for effecting movement of said controlling means to flow-interrupting position.

2. In a pumping system, in combination, a single acting pumping motor having a load, fluid connections leading to said motor, controlling means for said connections normally yieldingly maintained in flow-permitting position but having when closed an unbalanced pressure area by which it is held in closed position when moved thereto, means controlled by pressure built up in the non-working end of said pumping motor upon loss of pumping load for effecting movement of said controlling means to flow-interrupting position, and means by which said unbalanced pressure area may be rendered ineffective to hold said valve closed.

3. In a pumping system, in combination, a single acting pumping motor, a load carried thereby, fluid connections leading to the motor, valve means for controlling said connections, a pressure fluid actuated member aligned with said valve means and operatively connected thereto, means for precluding automatic valve reopening when the same closes completely, and means for subjecting said fluid actuated member to a compression pressure built up in said motor in the event that said motor loses its load.

4. In a pump controlling apparatus, controlling means including a valve casing, a valve seating

in the direction of flow through said casing and when closed having an unbalanced area maintaining it closed, a valve stem, a piston mounted on said valve stem, a cylinder in which said piston is reciprocable, a single acting pumping motor supplied with operating fluid under control of said valve means and having a cylinder, a piston therein, and a connection from the non-working end of said motor cylinder to said first mentioned cylinder together with means for venting normal pressure variations from said non-working end.

5. In a pumping apparatus, controlling means including a valve casing, a valve controlling flow through said casing, a valve stem, a piston mounted on said valve stem, a cylinder in which said piston is reciprocable, relatively yielding means for resiliently opposing movements of said valve by said piston insufficient to close the former, means for presenting a relatively substantial resistance to movements of said valve to closed position, and means for precluding return of said valve to open position when once closed, a single acting pumping motor supplied with operating fluid under control of said valve means and having a cylinder and a piston in said cylinder, said motor having means for venting normal pressure variations from its non-working end, and a connection from the non-working end of said motor cylinder to said first mentioned cylinder.

6. In a pumping apparatus, in combination, a pumping motor having a cylinder and a piston cooperating on the working stroke of said pumping motor to displace air, means permitting displacement of the air without the development of a substantial pressure during normal operation of the pumping motor but insufficient to prevent development of progressively increasing pressure on increases in speed of piston travel above a desired rate, and common means for controlling the normal operation of said pumping motor and for interrupting operation thereof entirely under certain conditions, including a fluid supply connection for said motor, a valve controlling said fluid supply connection, and controlling means for said valve including a fluid actuated member movable to close said valve, means for connecting said fluid actuated member with the space from which said piston displaces fluid, means for limiting opening movement of said valve to an amount corresponding to desired maximum pumping speed, and means for yieldably resisting movement of said fluid actuated member including means providing continuously a light opposition to movement of said member in valve closing direction and auxiliary means ineffective during minor movements of said member but presenting a stronger opposite to greater movements thereof and effective to preclude valve closure thereby except upon the subjection of said member to fluid pressures attendant upon serious loss of pumping load.

7. In a pumping apparatus, in combination, a pumping motor having a cylinder and a piston cooperating on the working stroke of said pumping motor to displace air, means permitting displacement of the air without the development of a substantial pressure during normal operation of the pumping motor, but insufficient to prevent development of progressively increasing pressure on increases in speed of piston travel above a desired rate, and means for controlling the operation of said pumping motor and for interrupting operation thereof entirely under certain conditions, including a fluid supply connection for said

motor, a valve controlling said fluid supply connection, and controlling means for said valve including a fluid actuated member movable to close said valve, means for connecting said fluid actuated member with the space from which said piston displaces fluid, means for maintaining said valve closed when complete closure is attained, and means for yieldably resisting movement of said fluid actuated member effective to maintain full opening at the desired speed of motor operation but yielding if said speed is exceeded.

8. In a pumping apparatus, in combination, a pumping motor having a cylinder and a piston cooperating on the working stroke of said pumping motor to displace air, means permitting displacement of the air without the development of a substantial pressure during normal operation of the pumping motor, but insufficient to prevent development of progressively increasing pressure on increases in speed of piston travel above a desired rate, and means for controlling the operation of said pumping motor and for interrupting operation thereof entirely under certain conditions, including a fluid supply connection for said motor, a valve controlling said fluid supply connection, and controlling means for said valve including a fluid actuated member movable to close said valve, means for connecting said fluid actuated member with the space from which said piston displaces fluid, means for yieldably resisting movement of said fluid actuated member effective to maintain full opening at the desired speed of motor operation but yielding if said speed is exceeded, and auxiliary means for yieldingly resisting movement of said fluid actuated member to close said valve preventing valve closure except on piston travel warranting interruption of motor operation.

9. In a pumping apparatus, in combination, a pumping motor having a cylinder and a piston cooperating on the working stroke of said pumping motor to displace air, means permitting displacement of the air without the development of a substantial pressure during normal operation of the pumping motor, but insufficient to prevent development of progressively increasing pressure on increases in speed of piston travel above a desired rate, and means for controlling the operation of said pumping motor and for interrupting operation thereof entirely under certain conditions, including a fluid supply connection for said motor, a valve controlling said fluid supply connection, and controlling means for said valve including a fluid actuated member movable to close said valve, means for connecting said fluid actuated member with the space from which said piston displaces fluid, means for yieldably resisting movement of said fluid actuated member, and latch means for holding said valve closed when said yielding means yields to a predetermined extent.

10. In a pumping apparatus, in combination, a pumping motor having a cylinder and a piston cooperating on the working stroke of said pumping motor to displace air, means permitting displacement of the air without the development of a substantial pressure during normal operation of the pumping motor, but insufficient to prevent development of progressively increasing pressure on increases in speed of piston travel above a desired rate, and means for controlling the operation of said pumping motor and for interrupting operation thereof entirely under certain conditions, including a fluid supply connection for said motor, a valve controlling said fluid supply con-

- nection, and controlling means for said valve including a fluid actuated member movable to close said valve, means for connecting said fluid actuated member with the space from which said piston displaces fluid, means for yieldably resisting movement of said fluid actuated member, latch means for holding said valve closed when said yielding means yields to a predetermined extent, and yielding means for preventing yielding of said first mentioned yielding means enabling said valve to move sufficiently to permit operation of said latch means during slight piston overspeeding.
11. In a pumping system, in combination, a single acting pumping motor having a pressure fluid moved work performing element, a pumping load moved thereby, fluid supply connections for the motor, and controlling means for said connections including a supply throttling and interrupting valve having means for yieldably maintaining the same normally open and means for maintaining the same closed, whenever moved to closed position, irrespective of cessation of the operating condition which effected closure, and means for partially closing the same on small reduction in pumping load to effect partially throttled but continued supply and complete closure on substantially complete loss of pumping load.
12. In a pumping system, in combination, a single acting pumping motor having a pressure fluid moved work performing element, a pumping load moved thereby, fluid supply connections for the motor, and controlling means for said connections including a supply throttling and interrupting valve having means for maintaining the same closed, whenever moved to closed position, irrespective of cessation of the operating condition which effected closure, and means actuated by fluid displaced by the pressure fluid moved work performing element for partially closing said valve means on small reduction in pumping load, to effect partially throttled but continued supply and complete closure on substantially complete loss of pumping load.
13. In a pumping system, in combination, a single acting pumping motor, a pumping load connected thereto by a rod line, a source of operating fluid supply for said pumping motor, and a single control valve intermediate said supply and motor including valve means having a pressure fluid control responsive to speed changes occurring during each single power stroke of the pumping motor and movable in a closing direction to accommodate and adjust fluid supply in accordance with any normal speed variations without closure, but completely closable on motor movement following rod line breakage and having means for maintaining the same closed until said means is rendered ineffective by intervention from outside said system.
14. In a pumping system, in combination, a single acting pumping motor having relatively movable cylinder and piston elements, a pumping load moved by said motor, said cylinder element having a connection for the discharge of fluid from the non-working end thereof during moving of said pumping load by said motor, a fluid supply for said motor, and a valve for throttling or completely interrupting fluid supply to said motor, said valve having provision for maintaining the same closed, whenever the same is moved to closed position, until said provision is rendered ineffective by intervention from outside said system, and means actuated by fluid discharged through said connection for partially closing said valve on small reduction in pumping load, to effect partially restricted but continued supply of operating fluid to said motor, and to effect complete closure of said valve upon substantially complete loss of pumping load.
